(57) **CLAIM**

We claim the ornamental design for a garage door sensor, as shown and described.

DESCRIPTION

FIG. 1 is a front and top perspective view of a garage door sensor of the present invention;

FIG. 2 is a rear and top perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown represent unclaimed subject matter and form no part of the claimed design.
